LOAD APPLICATION UNIT

James W. Gaines, Los Angeles, Calif., assignor to
North American Aviation, Inc.

Application October 15, 1951, Serial No. 251,405

12 Claims. (Cl. 73—88)

1

This invention applies to a load application unit and more particularly to a unit adapted to apply loads to curved or straight test panels.

Present day arrangements for applying loads to test a specimen normally involve units that are glued to the specimen. Each unit is separate and is backed up by a rigid metal plate. These units are normally attached to a test specimen by placing a vacuum blanket over the units so that the units may be held against the specimen by the force of a vacuum until the glue has set. The rigid metal plates must be shaped as nearly as possible to the contour of the test specimen which is a time consuming operation, and it is nearly impossible to form the plates to the exact contour required. As a result, there is a tendency to deform the test specimen when the plates are attached by means of the vacuum blanket. In addition, it takes a good deal of time to attach the plates as well as to form them and it is very difficult to remove the glue when the tests are completed. Solvents for the glue will injure a windshield canopy test specimen, and scraping of the glue will also result in damage to the specimen due to scratching. Arrangements utilizing vacuum cups as the load application units have been proposed, but these have proved unsatisfactory because they are difficult to seal around the edges and will not produce a uniform vacuum load throughout the entire area where the unit is attached. As a result these load units are poorly attached to the test specimen and will not withstand high loads. Further, these units will tend to distort the test specimen due to the non-uniform vacuum produced.

Accordingly, it is an object of this invention to provide a load application unit that may be easily and securely applied to a test specimen and may be quickly removed.

Another object of this invention is to provide a load application unit that does not require gluing to the test specimen.

A further object of this invention is to provide a load application unit that does not require the use of substances injurious to the test specimen.

An additional object of this invention is to provide a load application unit that will withstand heavy loads and will not cause distortion of the test specimen.

Still another object of this invention is to provide a load application unit having a plurality of load assuming members.

These and other objects of this invention will become apparent from the following detailed de-

2

scription taken in connection with the accompanying drawings in which

Fig. 1 is a perspective sectional view of the load application unit applied to a test specimen,

Fig. 2 is a fragmentary inverted perspective view illustrating an alternative construction of the non-porous sheet.

Fig. 3 is a plan view illustrating the use of a second sheet of non-porous material,

Fig. 4 is a view along line 4—4 of Fig. 3,

Fig. 5 is an elevation of a modification of the load application unit,

Fig. 6 is a plan view of portions of the bottom of a unit of the type shown in Fig. 5,

Fig. 7 is a sectional view of a unit of the type of Fig. 5 associated with porous sheets,

Fig. 8 is a sectional view of a pad and sheet formed from a single piece of material,

Fig. 9 is a sectional view of a pad and sheet formed from a single piece of material wherein the bottom portion is provided with grooves, and

Fig. 10 is a one-piece unit of the type of Fig. 5 associated with porous sheets.

Referring to the drawings, in a preferred em-

bodiment of this invention, load application unit 1 is made of a sheet of non-porous flexible material 2 to one side of which is applied a thicker pad 3 which is also of a flexible material such as sponge rubber. The pad may be attached to the sheet by bonding, gluing or other satisfactory methods and should be positioned in the central portion of the sheet so that the periphery 4 of the sheet extends beyond the pad on all sides. On the other side of the pad a plurality of flat, rigid plates 5 are attached by gluing or other suitable methods. These plates should be spaced from each other as illustrated in order to allow flexure of the unit. It is normally desirable to put a V-shaped groove 6 in the pad between the plates to facilitate flexure of the unit. Attached by screwthreads, welding or other suitable means to each plate 5 is a fitting 7 adapted to receive a load producing member such as wire cable 8. The unit may be constructed as large or as small as desired and as many plates 5 may be attached to the pad as necessitated by the size of the unit and the number of load producing members 8 to be attached. Means are also provided for producing a vacuum beneath sheet 2 which may be accomplished by providing a length of tubing 9 projecting through one of the plates, the pad and the sheet. This tubing opens to the bottom of sheet 1 and is adapted to receive a vacuum hose 10 on its other end. The vacuum hose is

connected with a suitable vacuum pump 19 for producing the vacuum.

There is, in this manner, provided a unit that is flexible and may be attached to a specimen of almost any contour or curvature whether convex or concave. When the unit is associated with such a test specimen 11 a vacuum line 10 is connected to exhaust the air from beneath sheet 2. The resulting vacuum will securely attach the unit to the test specimen, after which loads as desired may be applied through cables 8. Each plate member 5 may receive a load producing member if desired. Detachment of the unit from the test specimen is accomplished by merely releasing the vacuum beneath sheet 2 which allows easy removal of the unit from the test specimen.

As a vacuum is produced beneath sheet 2 the unit will be securely attached to the test specimen and will be able to withstand loads equal to the atmospheric pressure multiplied by the area beneath sheet 2 where the vacuum is produced. Despite the fact that flat, rigid plates 5 are utilized for load application members, there will be no distortion of a curved test specimen when the vacuum is applied because flexible pad 3 will distribute the forces between the test specimen and sheet 2 so that plates 5 will not tend to straighten out the surface of such a curved test specimen.

It is normally preferred to interpose a vacuum sealing material 12 beneath the projecting periphery 4 of sheet 2 in order to assure a complete vacuum beneath the sheet. This material may be zinc chromate, ordinary caulking compound or other suitable material. When the unit is removed from the test specimen this sealing material will require no scraping and can be easily washed off with a solvent that will not injure a transparent windshield canopy.

It is also generally desirable to provide a sheet of porous material 13 between sheet 2 and test specimen 11. Sheet 13 should be of lesser width and length dimensions than sheet 2—approximately the dimensions of pad 3—and positioned in the center so that the periphery 4 of sheet 2 projects beyond porous sheet 13 in all directions. This porous sheet may be of any suitable material such as wire screen or a loosely woven fabric such as burlap. The function of porous sheet 13 is to prevent sheet 2 from sealing itself off at a location other than the periphery of this sheet, thus assuring that there is a uniform vacuum throughout the area beneath pad 3.

Another method of assuring that the vacuum is uniform beneath sheet 1 is to provide the bottom surface of the unit with grooves 14 or other irregularities in the area beneath the pad portion in the manner illustrated in Fig. 2 in which the load application unit is inverted from the position shown in Fig. 1. With this modification it is unnecessary to use a porous sheet 13 because the grooves will permit complete exhaustion of the air from beneath the sheet and prevent sealing at positions other than the periphery of sheet 2.

In certain instances it may be desirable to provide a second sheet of non-porous material 15 as illustrated in Figs. 3 and 4. This sheet should be of a highly flexible material and may be a thin sheet of a plastic material such as a vinyl derivative. Sheet 15 should have an aperture 16 in its central portion dimensioned so as to admit pad 3 while allowing the periphery of the aperture to engage the periphery of sheet 2. Additional sealing material 12 should be provided

between sheet 15 and periphery 4 of sheet 2, and a ring of the sealing material may be provided between sheet 15 and test specimen 11 well beyond the periphery of sheet 2. The use of this additional non-porous sheet assures a complete vacuum beneath the load application unit and will assist in resealing around the periphery of the unit should the seal be broken.

A modification of this invention is illustrated in Fig. 5 in which the bottom surface of sheet 1 is provided with depending tabs 17. When a unit provided with these tabs is associated with a test specimen, tabs 17, sheet 2, and the test specimen cooperate to provide a plurality of separate chambers 18. A suitable vacuum aperture such as tubing 9 is provided to each of these chambers. When the unit is applied, vacuum sealing compound 12 may be disposed beneath each of the tabs to assure that the chambers are separately sealed from each other. To assure a complete and uniform vacuum beneath sheet 2, each chamber 18 may be provided with a sheet of porous material 13, as illustrated in Fig. 7, or the surface of sheet 2 may be provided with grooves 14 or other indentations as shown in Fig. 6 or of the type illustrated in Fig. 2.

When such a modified test unit is applied to a test specimen a separate vacuum line 10 may be attached to each of chambers 18 or these vacuum lines may be manifolded together by manifold 20, as shown in Fig. 5, if desired. The vacuum lines and manifold are connected with suitable vacuum pumps 19. Thus, for example, if failure of the test specimen is anticipated at a certain area a separate vacuum line may be applied to the chambers in that area while the other chambers may be manifolded together. Thus failure of the test specimen at the critical area will not effect adherence of the unit in other positions.

It is possible as a further modification to construct sheet 2 and pad 3 out of a single piece of material in any of the above described embodiments. Fig. 8 illustrates a pad and sheet of the type of Fig. 1 formed from one piece of material 21. In Fig. 9 is shown a one-piece pad and sheet unit 21 having grooves to assure complete exhaustion of air from beneath the unit in the manner in the embodiment of Fig. 2. A test unit having a plurality of chambers 18 yet made from a single piece of material is illustrated in Fig. 10.

It should be clearly understood that the above detailed description is to be taken by way of illustration only and not to be taken by way of limitation, the spirit and scope of this invention being limited only by the terms of the appended claims.

I claim:

1. A load application unit comprising a sheet of flexible material, one side of which is adapted to engage a test specimen and assume the contour thereof; a pad of flexible material attached to the opposite side of said sheet; a plurality of laterally spaced reinforcing members secured to said pad remote from said sheet, each of said reinforcing members being provided with means adapted to engage load producing means; and means for exhausting the air from beneath said sheet thereby securing said unit to said specimen.

2. A device as recited in claim 1 in which the periphery of said sheet of flexible material projects beyond said pad on all sides thereof, and includes in addition a second sheet of flexible non-porous material adapted to engage said periphery and said specimen.

3. A device as recited in claim 1 which includes in addition a sheet of porous material adapted to be interposed between said sheet of flexible material and said specimen with the periphery of said sheet of flexible material projecting beyond the periphery of said sheet of porous material.

4. A device as recited in claim 1 in which the surface of said sheet adapted to engage said test specimen is provided with groove means for facilitating the exhaustion of air from beneath said unit.

5. A load application unit comprising a sheet of non-porous flexible material one side of which is adapted to engage a test specimen and assume the contour thereof; a pad of flexible material attached to the opposite side of said sheet; a plurality of rigid plate members secured to said pad remote from said sheet; said plates being disposed in spaced relationship with each other for permitting flexure of said pad and said sheet; each plate being provided with means adapted to engage load producing means; said pad and said sheet having apertures therethrough for allowing exhaustion of air from beneath said sheet for holding said unit to said specimen.

6. A load application unit comprising a sheet of non-porous flexible rubber, the underside of which is adapted to complementarily engage a test specimen; a pad of flexible rubber attached to the opposite side of said sheet; a plurality of rigid metal plates attached to the surface of said pad remote from said sheet; said plates being disposed in spaced relationship with each other, said pad being provided with grooves between said plates for facilitating flexure on said unit, said unit being provided with an aperture communicating with the underside of said sheet; and means connected with said aperture for creating a vacuum between said sheet and said specimen or attaching said unit thereto.

7. A load application unit for a test specimen comprising a sheet of porous material engaging the surface of said specimen; a sheet of non-porous material adapted to overlie said porous sheet with its periphery extending beyond said sheet onto the surface of said specimen; a vacuum sealing substance disposed beneath the periphery of said non-porous sheet; a pad of flexible material having substantially the width and length dimensions of said porous sheet attached to the central portion of said non-porous sheet on the side remote from said porous sheet; a plurality of rigid plate members attached to said pad remote from said non-porous sheet, said

plate members being disposed in spaced relationship and adapted to engage load producing means; a second sheet of non-porous material adapted to overlie the periphery of said first mentioned non-porous sheet; and means for producing a vacuum between said first mentioned non-porous sheet and said specimen thereby securing said unit thereto.

8. A load application unit comprising an elongated flexible member, one side of which is adapted to engage a test specimen; a plurality of rigid plate members disposed in laterally spaced relationship and attached to said flexible member remote from said side adapted to engage a test specimen; and means for exhausting the air from beneath said flexible member for securing said unit to a test specimen.

9. A device as recited in claim 8 in which said side adapted to engage a test specimen is provided with a plurality of depending tab portions adapted to cooperate with said test specimen to provide a plurality of chambers therewith, and including means for evacuating each of said chambers.

10. A load application unit comprising a sheet of flexible material, one side of which is provided with a plurality of depending tab portions and adapted to engage the surface of a test specimen thereby cooperating with said specimen to provide a plurality of chambers between said sheet and said specimen; a pad of flexible material attached to the opposite side of said sheet; a plurality of rigid plates attached to said pad remote from said sheet in a spaced relationship with each other, said plates being provided with means adapted to engage load producing means; and means for evacuating each of said chambers for holding said unit to said specimen.

11. A device as recited in claim 10 in which said sheet of flexible material is provided with groove means between said tab portion for facilitating the exhaustion of air from said chambers.

12. A device as recited in claim 10 including in addition a sheet of porous material for each of said chambers and adapted to be received therein.

JAMES W. GAINES.
